IRONING BOARD

Filed April 8, 1920

FIG. 1.

FIG. 2.

FIG. 3.

J. Lutes. INVENTOR.

BY

W. Randolph Jr.

ATTORNEY.

UNITED STATES PATENT OFFICE.

JOHN LUTES, OF FERGUSON, IOWA.

IRONING BOARD.

Application filed April 8, 1920. Serial No. 372,305.

To all whom it may concern:

Be it known that I, JOHN LUTES, a citizen of the United States, residing at Ferguson, in the county of Marshall and State of Iowa, have invented certain new and useful Improvements in Ironing Boards; and I do hereby declare the following to be a full, clear, and exact description of the invention, such as will enable others skilled in the art 10 to which it appertains to make and use the same.

This invention relates to ironing boards and it consists in the novel features herein-after described and claimed.

15 An object of the invention is to provide an ironing board of simple and durable structure adapted to be applied to the edge of a table top or other support and which may be conveniently used for ironing garments or articles of apparel as for instance, skirts, bodies, sleeves and trousers.

With this object in view, the ironing board includes a relatively long and narrow panel provided at one end with a recess and 25 having blocks mounted upon its under side at the side edges of the recess and a prop or leg pivotally mounted between the blocks and having an end portion adapted to enter the recess when the ironing board is set up, 30 said prop having at one end a clamping head adapted to engage the upper surface of the table. The panel is provided upon its top side with a cleat which is disposed transversely of the panel and having one edge 35 flush with the inner end wall of the recess. The panel and the cleat are of wood and the grain of the wood of the cleat is disposed transversely of the grain of the wood of the panel and therefore a laminated structure is 40 provided whereby the parts effectually brace each other and splitting or warping of the parts is prevented.

In the accompanying drawings:—

Figure 1 is a perspective view of the iron- 45 ing board.

Figure 2 is a side elevation of the iron- 50 ing board folded.

Figure 3 is a fragmentary longitudinal sectional view through the board and prop at the clamp end.

Figure 4 is a transverse section through the structure along the pivot of the prop.

The ironing board comprises a panel 1 of wood and the said panel is relatively long,

narrow and thin in its respective longitudinal, breadth and thickness dimensions. The longitudinal edges of the panel from a point approximately mid-way between the ends thereof converge toward each other and toward one end of the panel. The panel is provided at its opposite end at a point midway between the side edges thereof with a recess 2. Upon the underside of the panel blocks 3 are mounted and the blocks are located at the opposite side edges of the recess 2. A prop 4 is pivoted between the blocks and when the device is not in use, the said prop may lie along the underside of the panel and approximately parallel thereto and in close proximity therewith. The prop 4 is provided at its shorter end portion with a notch 6 in which is located a clamping block or head 7. When the ironing board is set up the shorter end portion of the prop is disposed through the recess 2 and the clamping head 7 engages against the upper surface of the table top or support in a usual manner. The lower end of the prop 4 has contact with the surface of the floor. A cleat 8, of wood, is disposed transversely across the panel 1 and at the upper surface thereof. One edge of the cleat 8 is flush with the inner end wall of the recess 2. The grain of the wood of which the cleat 8 is composed is disposed transversely to the grain of the wood of the panel 1 and consequently a laminated structure is provided and these parts brace each other and prevent warping or splitting.

From the foregoing description taken in conjunction with the accompanying drawing, it will be seen that an ironing board of simple, and durable structure is provided, and while the same is composed of relatively light and fragile material, the parts are so arranged as to prevent distortion, warping, or splitting under the conditions of moisture and temperature to which the structure will be subjected when in use.

Having described the invention, what is claimed is:—

A device of the class described having a board provided with a slot extending inwardly from one end thereof, a prop pivoted to the board and movable in said slot, said prop having a notch in one side thereof below the upper end, a block in said notch whereby it will be overlapped by a portion

2
of the prop and reinforced from above, said block having its under surface movable into parallelism with the board, the block being wider than the prop, the said surface and
5 adjacent end of the board being adapted to grip a support, and said block being movable beyond the adjacent end of the board to clear the same and enable the prop to be

folded flat against the under surface of the board.

In testimony whereof I affix my signature in presence of two witnesses.

JOHN LUTES.
